Attorney.

UNITED STATES PATENT OFFICE.

LOUIS MINCH, OF HIGHLANDTOWN, MARYLAND.

CASK.

SPECIFICATION forming part of Letters Patent No. 355,195, dated December 28, 1886.

Application filed August 26, 1886. Serial No. 211,910. (No model.)

To all whom it may concern:

Be it known that I, LOUIS MINCH, a citizen of the United States, residing at Highlandtown, in the county of Baltimore and State of Maryland, have invented certain new and useful Improvements in Casks; and I do hereby declare the following to be a full, clear, and exact description of the invention, such as will enable others skilled in the art to which it appertains to make and use the same.

My invention relates to improvements in the construction of casks or large barrels for beer and other malt liquors.

The object of the invention is to provide means for gaining access to the interior of the large casks or barrels used in breweries, &c., for storing beer, ale, or other malt liquors, wines, &c., and from which these are drawn into small kegs or bottles; and it is well known that said casks or barrels require thorough cleaning or repitching, &c., and therefore access must be had to the interior, and a large opening is required, which must be closed securely and so as to prevent leakage, as the pressure in such casks or barrels is often very great, being caused by the generation of carbonic and other gases, or also by fermentation, &c.; and with this object in view my invention consists in providing said casks, barrels, or hogsheads with a large opening in the head for gaining access to the interior, and closing said opening by a plate bedded against a packing in the edges of a frame secured to the cask on its sides and top, while the lower ends of its sides, as well as the bottom of the plate, fit into the croze of the cask to prevent leakage, and said plate is arranged on the inside of the barrel or cask and fits against said metal frame secured, as stated, to the head of the barrel or cask, and said plate is held in place by a strong bolt and clamping-bar.

It also consists in the construction of certain details and the arrangement of parts, as will be more fully described hereinafter, and specifically pointed out in the claims, reference being had to the accompanying drawings and the letters of reference marked thereon.

Similar letters indicate like parts in the different figures of the drawings, in which—

Figure 1 represents a longitudinal section of a barrel having my improvement attached.

Fig. 2 is a front view of the frame and plate for the opening. Fig. 3 is a vertical section on the line *x x* of Fig. 2.

In the drawings, A represents a large cask, 55 barrel, or hogshead having the heads *a* and *b*. In the head *a* an opening, *c*, is made for gaining access to the interior of said cask, &c. This opening is made close to the bottom, and is preferably of the shape shown in Fig. 2, in 60 which the upper part is semicircular, while the lower part conforms to the contour of the cask or barrel. Around the opening, on three sides, is closely fitted a frame, B, of metal or other suitable material, which is securely bolted to 65 the head of the barrel by bolts *d*, while its lower side fits into the croze of the cask, notches being cut in the croze to receive the flanged ends of the frame B. The frame is made beveling, and has a flange, *e*, bearing against the inner 70 side of the head, while another flange or seat, *f*, serves as a bearing-surface for the plate C. This plate is rabbeted on three of its edges, and between it and the frame any suitable packing, 75 *f'*, of rubber or other material, is placed, while the lower edge of said plate is placed in the croze of the cask to form a tight joint when the plate C is clamped to its seat. A bolt, D, passes through the plate, and a clamping-bar, E, extends across the frame on its outer side and 80 firmly secures the plate in its place.

To prevent any displacement of the frame B transversely from the head *a*, suitable wood-screws or bolts, *g*, are employed, as best seen in Fig. 3, while the longitudinal strain is taken 85 by the bolts *d*, which are provided with nuts *d'*, to secure them more firmly and prevent the "pulling out of the head."

The size of the frame and door-plate may be varied as desired and according to the size of 90 the barrel or hogshead for which it is intended. Any number of bolts may be used to secure the frame.

The operation is as follows: The frame is first securely fastened in place on the head of the 95 barrel by the longitudinal and transverse bolts, and after it has been washed out, repaired, scraped, pitched, &c., the plate is drawn up to its recessed seat, and is then secured by the clamping-bar and bolt and nut. 100

It will be readily seen and understood by those skilled in the art that this device is very

simple and efficient. It can be readily applied to old as well as new barrels, casks, &c. It affords an easy and large space for gaining access to the interior. The gum washer may be 5 inserted in a groove, if desired.

Having thus described my invention, what I claim, and desire to secure by Letters Patent, is—

1. The combination of a barrel, cask, &c., 10 having a metal frame secured by bolts on three sides, and with the lower ends of its sides in the croze, as shown, with a plate rabbeted on three of its edges and secured against a packing on the seat and in the croze by a bolt and nut and 15 a clamp-bar, all as shown and specified.

2. The combination of a barrel, cask, &c., having a frame, B, provided with a flange, e, and seat f, and secured by bolts d and g, with a plate, C, having rabbeted edges and secured by a bolt, D, and clamp-bar E, all arranged as 20 shown and herein set forth.

In testimony whereof I hereto affix my signature in presence of two witnesses.

LOUIS MINCH.
